Primary Examiner — Kelley A Donnelly(74) *Attorney, Agent, or Firm* — Rosenberg, Klein & Lee(57) **CLAIM**

The ornamental design for a storage box, as shown and described.

DESCRIPTION

FIG. 1 is a perspective view of my new design for a storage box;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is an enlarged view of the circled area in FIG. 6;

FIG. 8 is a bottom plan view thereof; and,

FIG. 9 is an enlarged view of the circled area in FIG. 8.

The broken lines showing a box cover in FIGS. 1 to 9 represent environmental structure and form no part of the claimed design.
